OIL BURNER

Original Filed March 11, 1940

UNITED STATES PATENT OFFICE

2,360,503

OIL BURNER

Allen P. Livar, Dayton, Ohio, assignor to Chrysler Corporation, Detroit, Mich., a corporation of Delaware

Original application March 11, 1940, Serial No. 323,375. Divided and this application January 27, 1941, Serial No. 376,115

1 Claim. (Cl. 158—76)

This application is a division of Serial No. 323,375 of Allen P. Livar, for Oil burner, filed March 11, 1940, now Patent 2,301,060, of November 3, 1942.

Specifically the invention comprises a pressure atomizing oil burner including a blast tube into which air is directed tangentially and forwardly at diametrically opposite points so as to produce a whirling stream of air into such tube.

An object of the invention is to provide means for adjusting the point of impingement cone of fuel spray and a rotating cylinder of air issuing from the blast tube, to provide for this purpose a cone which at all positions of adjustment will insure this body of air striking the cone of oil spray at the same distance from the nozzle orifice, and to provide means for manufacturing the cone in a position normal to the longitudinal axis of the blast tube.

Other objects of the invention will be more apparent from the following description taken in connection with the accompanying drawing, wherein:

Fig. 1 is a vertical sectional view through a burner embodying the invention.

Fig. 2 is a transverse section taken on line 2—2 of Fig. 1.

The improved burner is described in detail in the aforesaid patent and in so far is pertinent to the present invention comprises a principal casting, generally designated by the numeral 10, including parts of the blower housing or housings, one such part being shown at 11; blower outlet or outlets, one of which is shown at 12; and a blast tube 13. A hood 14 is supported on the part 11 and encloses the power assembly comprising blower wheels (not shown), motor 15 and pump 16 which are connected by a belt 17 and mounted on a supporting plate 18. The hood also encloses a transformer 19 and its hinged mounting plate 20. The protective closure formed by the hood 14 has an opening at the bottom adjacent the rear end of the blast tube which is partially blocked by the transformer 19 and a further opening at the front above the top of the blast tube which is partially blocked by the motor 15.

The motor 15 is provided with a voltage control device 21 of the character conventional to apparatus of this type and a shaft 22 which extends through a blower inlet opening for connection to the blower wheel (not shown), as disclosed in the parent patent.

The fuel pump 16 is suitably connected with a supply line (not shown) and has a pressure regulatory device 24 to which is connected a tube 25 leading to the nozzle. The tube 25 is adapted to extend downwardly between the hood 14 and the outer edge of the transformer mounting plate 20 and thence upward through an opening 26

provided in the plate 20 to connect with an elbow 27 on a short section of pipe 28 projecting rearwardly from the recessed central portion 29 of a blast tube closing cap 30. A passage 31 is drilled through the portion 29 and a nozzle supporting tube 32 extends through the blast tube 13 from the passage 31 and supports the nozzle 33 at its outer end. The elbow 27, tube 28, cap 30, tube 32, and nozzle 33 are assembled with an air volume adjusting damper 34, electrodes 35, and three-legged centering spider 36 to complete a nozzle assembly which is removable as a unit from the blast tube 13.

The power assembly supporting plate 18 is supported principally by resilient bumpers 37 fastened to the lower end of the supporting plate and resting in an inverted channel member 38 carried by the blower housing. The center of gravity of the power assembly is preferably to the rear of the member 38 and the plate 18 is restrained from tipping rearwardly by a bolt 39 mounted in a boss 40 on the tube 13. The upper end of the bolt 39 is provided with a nut 41 and is enclosed in a flanged spacer 42.

The transformer 19 is provided with inwardly extending insulators, one of which is shown at 43, surrounding transformer terminal contacts 44 which are spaced above the center of the blast tube 13 and at each side of the centerline thereof substantially in line with but above the rear ends of the electrodes 35. The electrodes extend through the recessed central portion 29 of the blast tube cap 30, being insulated therefrom by insulators 45 and retained in adjusted position thereon by a clamp 46. The rear of the electrodes are threaded to clamp thereto, as by suitable lock nuts, the lower end of the leaf springs, one of which is shown at 47 made of a conductive, resilient material such as phosphor bronze. The free end portions of the spring 47, which constitute nozzle assembly contact members, are in such position as to be engaged and bent inwardly by the respective terminals 44 when the transformer is in its assembled position as shown.

As pointed out in the parent patent, the apparatus is operable to introduce into the blast tube 13 two streams of air entering at diametrically opposed points in substantially tangential and forwardly inclined directions resulting in a whirling cylinder of air moving forward through the blast tube. In order to control the volume of air admitted to the blast tube so that the flame characteristics may be regulated thereby, there is provided the adjustment damper 34 which is cylindrically shaped and rotatably mounted in the blast tube 13 having such clearances therewith as to permit rotation thereof but not undue leakage thereby. The cylinder 60 is provided with a rear flange 48 which is rotat-

ably journalled on the trunnion provided by the inwardly recessed portion 29 of cap 30 and which abuts the inner face of the flange of the cap. The cylinder is provided with a pair of longitudinally extending openings 49 and 50 respectively at the bottom and top thereof. Rotation of the cylinder effects a change in the volume of air admitted to the blast tube 13.

In order to rotate the cylinder the flange of the cap 30 is provided with an arcuate slot 51 of such length as to limit rotation of the damper between selected extreme positions. The stem of a thumb screw 52 extends through the slot 51 into the flange 48 of the cylinder and also through an adjusting lever 53 pivotally mounted on the section of tubing 28 and retained thereon by the elbow 27. The lever 53 may be shifted by releasing the screw 52 to adjust the damper 34 and hence the quantity of air admitted to the tube. This adjustment can be made during operation of the burner.

The construction of the damper 34 provides simultaneous and equal adjustment of the air streams and by regulating the volume of air at the outlets of the blowers the air stream is free from pulsations which are present when the control is at the blower inlet.

In order to obtain further adjustment of the flame characteristics there is provided means for adjusting the point of impingement of the cone of fuel spray issuing from nozzle 33 and the rotating cylinder of air issuing from the blast tube. As clearly seen in Fig. 1 the end of the blast tube is partially obscured by an end cone 54 having a central aperture large enough to permit the cone of spray to issue therethrough without impingement, but the diameter of which aperture is substantially less than the diameter of the blast tube. The inner surface of the end cone is curved so as to restrict the rotating cylinder of air without interfering with the rotation thereof and the angularity thereof is such as to direct the air through the cone of spray for intimate mixture therewith a short distance beyond the end of the blast tube. The end cone 54 is an important adjunct of the oil burner since it controls the point of mixture of the fuel and combustion supporting air; hence the longitudinal spacing of the orifice of the end cone from the orifice of the spray nozzle is important and changes thereof regulate the thoroughness of combustion and adjust the shape of the flame to various shapes and sizes of fireboxes. It is also necessary to adjust the end cone for different spray nozzles, there being nozzles available having different angles of spray.

In order to adjust the end cone while the oil burner is in operation, the end cone is provided with a cylindrical guiding flange 55 loosely fitting the interior wall of the blast tube 13, and it is attached at its lower extremity to a bar 56 extending along a channel or groove 57 at the bottom of the blast tube, which channel is provided for the purpose of maintaining the outer edge of the end cone exactly normal to the longitudinal axis of the blast tube so that the cone of air strikes the cone of oil spray at the same distance from the nozzle orifice at all points. The channel or groove 57 terminates at its rear end in a shoulder 58 which acts as a limiting abut-

ment by engaging a bend 59 in the rear end of the bar 56. Immediately adjacent the bend there is attached a threaded member 60 which extends downward through a longitudinal slot 61 in the bottom of the draft tube. The horizontal, free end 62 of the bar closes the portion of the slot 61 to the rear of the threaded member 60 and a small channel-shaped member 63 loosely mounted on the threaded member 60 closes the portion of the slot 61 in advance of the threaded member 60. A wing nut 64 is screwed onto the threaded member 60 to retain the channel member 63 and to clamp the bar and channel member in adjusted position so as to block the slot 61 against leakage and retain the end cone 54 in adjusted position. The nut 64 is placed immediately in advance of the standard upon which the burner rests so as to be available to the operator for substantially simultaneous adjustment of the damper 34 and the cone 54.

In operation the motor 15 drives the pump 16 causing fuel to be forced through the tube 25 and the tube 32 and to be sprayed through the nozzle 33. Simultaneously air is drawn upwardly around the transformer 19 and around the motor 15 into the blower inlet where the blowers force it downward, then tangentially into the blast tube at the upper and lower points to create a spiralling cylinder of air pressure. This body of air moves forward and is caused to be discharged through the cone of oil spray by the end cone 54, a spark being simultaneously created by the electrodes 35 which ignites the fuel and air mixture.

Having described a preferred embodiment of my invention it should be apparent to those skilled in the art that the same permits of modifications in arrangement and detail. All such as come within the scope of the following claim are considered a part of my invention.

40 I claim:

In an oil burner of the pressure atomizing type including a blast tube, blower means for forcing air through said blast tube and fuel spraying means comprising a fuel atomizing nozzle located centrally of and adjacent the end of said blast tube; an end cone mounted in the front end of said blast tube for constricting the air stream being forced therethrough by said blower means and directing the air stream through the spray issuing from said fuel atomizing nozzle adjacent the end of said blast tube; means for varying the longitudinal distance between the tip of said fuel atomizing nozzle and the outer edge of said end cone for altering the point of impingement of the air stream and spray comprising a bar extending rearwardly through the blast tube from said end cone, clamping means including a part extending from the rear end of said bar through a longitudinal slot in the lower part of the rear end of said blast tube; and means for maintaining the outer edge of said end cone in a plane normal to the longitudinal axis of said blast tube comprising a longitudinal groove in the bottom of said blast tube within which said bar is located and freely slidable for longitudinal adjustment of said end cone, said groove and said bar having complementary shoulders for limiting the extent of outward movement of said end cone.
